UNITED STATES PATENT OFFICE

2,542,204

ELECTRIC FAN

Edward C. Moore, Uniontown, Ala.

Application November 15, 1946, Serial No. 710,098

1 Claim. (Cl. 230—259)

1

This invention relates to electric fans, and more particularly to an electric fan of the vertical type.

A main object of the invention is to provide a novel and improved electric fan which is very simple in construction, neat in appearance, and which will effectively distribute and circulate the air in a room in all directions from the position of the fan.

A further object of the invention is to provide an improved electric fan of the vertical axis type, said fan being very inexpensive to manufacture, efficient in performance and quiet in operation.

Further objects and advantages of the invention will become apparent from the following description and claims, and from the accompanying drawings, wherein:

Figure 1 is an elevational view of an electric fan constructed in accordance with the present invention.

Figure 2 is an enlarged view similar to Figure 1 but with parts of the structure broken away to show the interior details thereof.

Figure 3 is a top plan view of the fan shown in Figure 1.

Referring to the drawings, 11 designates a housing comprising a relatively large circular base portion 12 upon which is secured a vertical barrel portion 13. Barrel portion 13 comprises an upper segment 22 and a lower segment 23, secured together by bolts 24 passing through the lower portion of upper segment 22 and threadedly engaging raised internal lugs carried by the upper portion of lower segment 23. Lower segment 23 has a top wall 14. Resting on said top wall 14 is a vertically positioned electric motor 15 secured to upper segment 22 by bolts 25. The shaft 16 of motor 15 coincides with the vertical axis of barrel portion 13. The top of barrel portion 13 is open, as shown in Figure 2, and the top of motor 15 is substantially flush with the top of said barrel portion so that shaft 16 need only extend a short distance above the top of the motor. Rigidly secured to the top end of shaft 16 is a substantially flat blade 17 of relatively large area, said blade being symmetrical with respect to its vertical axis, said vertical axis coinciding with the motor shaft axis. Blade 17 is shown as being generally oval in shape but may be varied from the shape shown so as to approach circular shape if so desired.

Rigidly secured to the top rim of barrel portion 13 is a guard 18 of wire mesh or the like which surrounds the rotating blade 17 when the fan is in operation.

2

Barrel portion 13 is formed with a plurality of ventilating openings 19 arranged so as to permit air currents to enter said barrel portion and circulate through the motor casing to prevent excessive heating of the motor. Wall 14 is formed with a central opening 20 through which said air currents may pass into the motor casing. The ventilating currents circulate upwardly through the motor casing and leave barrel portion 13 through the open top end thereof.

A control switch 21 is mounted on barrel portion 13 to turn the fan on and off.

While a specific embodiment of a vertically mounted electric fan has been disclosed in the foregoing description it will be understood that various modifications within the spirit of the invention may occur to those skilled in the art. Therefore it is intended that no limitations be placed on the invention other than as defined by the scope of the appended claims.

What is claimed is:

In an air-circulating fan, a base portion adapted to be supported in a horizontal plane, a vertically-disposed cup member having one end open and having the other end fixedly supported on said base portion, a horizontally-disposed wall positioned adjacent the open end of said cup member and fixedly secured to the latter, another cup member having one end open, the open end of said cup member being positioned in end to end abutting relation with respect to said first-named cup member, a vertically-disposed flat blade positioned above said last-named cup member and pivotally mounted thereon for rotation about a vertical axis, power means fixedly secured on said horizontally-disposed wall and positioned within said last-named cup member for effecting the rotation of said blade about said vertical axis, and a cage positioned in surrounding relation with said blade and fixedly secured to said last-named cup member.

EDWARD C. MOORE.
